WASHING MACHINE

Filed Dec. 29, 1923

2 Sheets-Sheet 2

UNITED STATES PATENT OFFICE.

FRED JAMES HENRY, OF DETROIT, MICHIGAN.

WASHING MACHINE.

Application filed December 29, 1923. Serial No. 683,479.

To all whom it may concern:

Be it known that I, FRED JAMES HENRY, citizen of the United States, residing at Detroit, in the county of Wayne and State 5 of Michigan, have invented certain new and useful Improvements in Washing Machines, of which the following is a specification.

This invention relates to certain new and useful improvements in washing machines, 10 and has particular reference to washing machines of the motor driven clothes pounder type.

The primary object of the invention is to provide a washing machine of the above 15 kind which is extremely simple and durable in construction and which will be effective in its washing operation.

Still another object of the invention is to provide a washing machine of the above 20 character which may be manufactured and marketed at a low cost and which embodies simple and durable parts, so constructed and co-related as to produce a machine which will require comparatively little attention 25 and which may be operated for a long continued period without becoming out of order.

A still further object of the invention is to provide an effective washing machine 30 which will be placed into use without the requirement of special skill and which is of generally improved construction.

Still another object of the invention is to provide a washing machine wherein vertically reciprocable slide rods are provided 35 in the clothes receptacle and operatively connected in a novel and improved manner to a driving motor disposed beneath said receptacle, the slide rod having clothes 40 pounding vacuum cups upon their upper ends.

With the above general objects in view, and others that will become apparent as the 45 nature of the invention is better understood, the same consists in the novel form, combination, and arrangement of parts herein-after more fully described, shown in the accompanying drawings and claimed.

In the drawings, wherein like reference 50 characters indicate corresponding parts throughout the several views:

Figure 1 is a front elevational view of a washing machine constructed in accordance with the present invention.

Figure 2 is an end elevational view of 55 a device shown in Figure 1, partly broken away and in section.

Figure 3 is a horizontal sectional view taken substantially upon the line 3—3 of 60 Figure 1, and,

Figure 4 is an elevational view of one of the slide rods and its attached clothes pounding vacuum cup.

Referring more in detail to the drawings, the present invention embodies a rigid 65 frame composed of four corner posts 5, that are rigidly connected by means of suitable superimposed sets of horizontal braces as at 6, 7 and 8 respectively, the braces 6 being provided adjacent the lower ends of the 70 corner posts 5 and supporting a platform 9 through the corners of which the uprights 5 pass, and the braces 7 connecting the corner posts 5 at a point adjacent to and above the platform 9 and supporting a second 75 platform 10 thru the corners of which the corner posts 5 also extend. The upper brace rods 8 and a rectangular frame 11 rigidly connect the corner posts 5 at the upper ends of the latter, and disposed upon the platform 10 within the space and bounded by the corner posts is a closed receptacle 12 that is of a height to extend from the platform 10 to the top of the corner posts 5 and which has its corners of rounded form 85 so as to guard against undue deposit of dirt in the corners and to permit or facilitate ready cleaning thereof. Any suitable form of removable or other cover 13 is provided for the top of the receptacle 12. 90

Disposed within and projecting upwardly from the bottom of the receptacle 12 adjacent the ends thereof are a pair of tubular standards 14, and projecting upwardly through the bottom of the receptacle 95 12 and through the standards 14, and projecting upwardly thru the bottom of the receptacle 12 and through the standards 14 are vertical slide rods 15 that are provided upon their upper ends with cross bars 16 100 of arched or curved form and upon the opposite ends of which are suitably secured clothes pounding vacuum cups 17. The upper ends of the standards 14 are disposed slightly above the proper water level of 105 the receptacle 12 so that water will not leak from the receptacle and the upwardly curved form of the cross bars 16 insure

lowering of the clothes pounding vacuum cups 17 beyond the upper ends of the standards 14 for effective action upon the clothes.

Journalled upon bearing brackets 18 that are fixed upon the lower platform 9 centrally of the latter is a horizontal transversely extending shaft 19 upon the ends of which are secured crank members 20, preferably in the form of discs having crank pins 21 eccentrically fixed thereto. The lower ends of each of the slide rods 15 project below the platform 10 and is formed with a horizontal cross piece 22 having an elongated slot 23. Each of the crank pins 21 works within a slot 23, so that when the shaft 19 is rotated, vertical reciprocation of the slide rods 15 is effected, and the pins 21 are so related as to insure upward movement of one of the slide rods 15 while the other of said rods is moved downwardly, thereby effecting alternate operation of the clothes pounding vacuum cups upon the clothes at the opposite ends of the receptacle 12.

25 A jack shaft 24 is suitably journalled rearwardly of the shaft 19 and parallel with the latter and secured upon one end portion of the shaft 24 is a pulley 25 that is operatively connected to the shaft 19 thru the medium of a belt 26 that passes around the pulley 25 and also around a relatively larger pulley 27 secured upon the shaft 19 intermediate its ends. Upon the other end portion of the shaft 24 are mounted fast and loose pulleys 28 and 29 respectively.

30 Suitably mounted upon the platform 9 in front of the shaft 19 is a motor 30 whose armature shaft 31 extends parallel with the shaft 19 and has fast and loose pulleys 32 and 33 respectively, mounted thereon, the pulleys 32 being aligned with the pulley 28 and the pulley 33 being aligned with the pulley 29. A belt 34 is employed for simultaneously engaging the pulleys 32 and 28 45 so as to transmit motion from the motor shaft 21 of the shaft 24 or to be shifted to the loose pulleys 33 and 29 when it is desired to render the washing machine inoperative. The shifting of the belt 34 may be effected by any suitable means such as a belt shifting lever 35 suitably mounted adjacent the front of the machine and operatively associated with said belt 34 as shown more clearly in Figure 3.

50 At one end of the machine and adjacent a corner of the machine frame, the lower platform 9 is provided with an extension as at 36, to which is secured a suitable gear casing 37 fixed to the lower end of a vertical post 38, in which is journalled a shaft as indicated by dotted lines at 39 in Figure 1, and the lower end of this shaft 39 is operatively connected to the end of the armature shaft 31 by means of a bevelled gearing generally indicated at 40 that is arranged with-

in the gear casing 37. The post 38 projects through extensions formed upon the upper platform 10 and the frame 11 and is connected at its upper end to a second gear casing 21 supported by the extension of the frame 11. A conventional form of wringer comprising inter-gearred rollers 42 is disposed at the ends of the machine against the casing 41 and the shaft of one of the wringer rollers 42 is connected to the upper end of the shaft 39 by means of a bevelled gearing as at 43 arranged within the gear casing 41. Any suitable means controllable by the lever 44 may be provided for connecting or disconnecting the shaft of a driven roller of the wringer from the shaft 39 so as to render the wringer operative or inoperative at will. It is to be understood that the wringer may be of that type mounted to swing horizontally about the axis of the post 38 as is well known in the art. Suitably mounted beneath the upper platform 10 is means for facilitating application of heat to the bottom of the receptacle 12 and this means may embody a gas burner 45 having an inlet pipe 46 adapted to be coupled to a suitable gas supply pipe and including a control valve 47.

55 In operation, the motor 30 is started so as to cause rotation of the shaft 31 and when the belt 34 is disposed upon the pulleys 28 and 32, rotation of the shaft 31 is communicated to shaft 19 through shaft 24 and the pulleys 25 and 27 and belt 26. This imparts rotary motion to the crank members 20 and by reason of the engagement of the pins 21 thereof in the elongated slot 23 of the cross pieces 22 provided on the lower ends of the vertical slide rods 15 the latter are vertically reciprocated so as to cause a pounding and suction action on the clothes through the medium of the vacuum cup 17, the pounding operation alternating at opposite ends of the receptacle 12. By swinging the lever 35 the belt 34 may be shifted to the pulleys 29 and 32 for rendering the machine temporarily inoperative while the motor 30 continues to operate. By swinging the lever 44, the motion which is constantly communicated to the shaft 39 from the motor shaft 31 may be transmitted to the rollers of the wringer for rendering the latter operative.

60 From the foregoing description, it is believed that the construction and operation as well as the advantages of the present invention will be readily understood and appreciated by those skilled in the art.

65 What I claim as new is:

70 A washing machine comprising a receptacle, tubular members mounted upon the bottom thereof and in the vicinity of the ends thereof, rods mounted for vertical sliding movement in the tubular members, cross bars mounted at the upper ends of the rods 75

and having downwardly curved end portions, vacuum cups carried at the ends of the cross bars, means for reciprocating the rods simultaneously in opposite directions, the space within the receptacle between the standards being unobstructed and the receptacle having curved lower edge portions, the arrangement being such that as the cups reciprocate in a liquid contained with-

in the receptacle the said liquid is swashed back and forth from one end of the receptacle to the other and whereby the said liquid may pass transversely through the texture of the fabric which are being washed.

15

In testimony whereof I affix my signature.

FRED JAMES HENRY.
